UNITED STATES PATENT OFFICE.

CHARLES W. THOMAS, OF TENAFLY, NEW JERSEY, ASSIGNOR TO H. MAIMIN CO., INC., A CORPORATION OF NEW YORK.

DESIGN FOR A HOUSING FOR CLOTH-CUTTING MACHINES.

46,919.

Specification for Design.

Patented Feb. 2, 1915.

Application filed October 10, 1914. Serial No. 866,138. Term of patent 7 years.

To all whom it may concern:

Be it known that I, CHARLES W. THOMAS, a citizen of the United States, residing at Mountain Road, Tenafly, New Jersey, have invented a new, original, and ornamental Design for a Housing for Cloth-Cutting Machines, of which the following is a specification, reference being had to the accompanying drawings, forming part thereof.

Figure 1 is a side elevation, and Fig. 2 is a plan view of a housing for cloth cutting machines, of my new design.

Copies of this patent may be obtained for five cents each, by addressing the "Commissioner of Patents, Washington, D. C."

I claim—

The ornamental design for a housing for cloth cutting machines, as shown.

In testimony whereof, I, affix my signature, in presence of two witnesses.

CHARLES W. THOMAS.
